UNITED STATES PATENT OFFICE

CHARLES N. CORYELL, OF MAMARONECK, NEW YORK

POLYGON VANITY CASE

Application filed February 18, 1928. Serial No. 255,291.

The invention relates in general to containers and, more particularly, to vanity cases of the type carried by women and holding toilet articles, such as powder, mirror, etc.

In vanity cases it is desirable that the case be of sufficient volume to hold the necessary articles and yet appear neat and small. Furthermore, it is desirable that the case be of strong, rugged and yet inexpensive construction.

According to the invention, a vanity case is provided having side walls of polygonal shape and top and bottom walls having flat annular portions and convex domed center portions. The vanity case may be of the double compact type or it may be of a single compact type. In the case of the double compact type, a third section may be provided containing a mirror. Each top and bottom cover may be provided with a bezel ring for holding the compact or other toilet article in the domed bottom. The covers may be hingedly connected at one of their straight sides and a novel catch may be provided in the form of a small flat plate hinged to one of the covers and connected to the other by means of a pin and hole engagement. The mirror section may be hinged to one of the bezel rings by placing the knuckle attached to the mirror section against the flat top of one of the bezel rings and passing a pintle wire through the knuckle and into the bezel ring.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a plan view of the case.

Fig. 2 is a side elevation.

Fig. 3 is a view of the case in open position.

Fig. 4 is a side elevation in open position.

Fig. 5 is a cross section taken on the line 5—5 of Fig. 3.

Fig. 6 is a detail on the line 6—6 of Fig. 5.

Fig. 7 is a section on the line 7—7 of Fig. 3.

Fig. 8 is a detail taken on the line 8—8 of Fig. 3.

In the following description and in the claims parts will be identified by specific names for convenience, but they are intended to be as generic in their application to similar parts as the art will permit.

Like reference characters denote like parts in the several figures of the drawing.

In the drawings accompanying and forming part of this specification, a practical commercial embodiment of the invention is shown; but as such illustration is primarily for purposes of disclosure, it will be understood that the structure may be modified in various respects without departure from the broad spirit and scope of the invention as hereinafter defined and claimed.

Referring now to the drawing, the case comprises a top cover 1, a base cover 2 hingedly connected thereto, and a mirror section 3 hingedly connected to the base cover.

The base cover 2 is made from sheet material and has its side wall 4 in the shape of a polygon, illustrated in this particular embodiment as an octagon. The bottom wall 5 comprises a flat annular portion 6 adjacent to the side wall 4 from which springs a circular, convex dome portion 7. Secured within the base cover is a bezel ring 8 having an outer octagonal flange 9 fitting the side wall 4 and an inner cylindrical circular flange 10, these flanges being connected by a flat portion 11. Connected to the inner circular flange 10 is an inwardly and downwardly extending curved flange which ends in a depending circular flange 12. The circular flange 12 has outwardly struck projections 13 for the purpose of retaining the compact 14 in place. The compact 14 shown is the usual commercial compact comprising a metal convex backing 15 filled with powder or rouge 16.

The top cover 1 is of substantially the same

construction as the base cover 2. It comprises the octagonal side walls 18, the bottom wall 19 having the flat portion 20 and the circular dome portion 21.

5 Disposed in the top cover is a bezel ring 22 shown most clearly in Fig. 7 and comprising a flat portion 23 having a polygonal edge fitting the side walls and a depending circular inner flange 24. This flange is provided 10 with struck-out portions 25 which detachably retain the compact 26 in the cover. This compact is the usual commercial compact with a metal convex backing 27 filled with cosmetic material 28, such as face powder.

15 The two covers 1 and 2 are hinged together by a hinge 31 which is made up of a central hinge knuckle 32 integral with the wall 18 of the top cover and two end knuckles 33 integral with the wall 4 of the base cover. A 20 suitable pintle 34 passes through the hinge knuckles 32 and 33 and is secured to the end knuckles.

25 The mirror section 3 comprises a body 134 made up of a flat bottom 35, the sheet metal being bent and folded back to form an annular flange 36 and then bent at right angles to form a cylindrical flange 37. Disposed within the body 34 is padding 38 and the usual mirror 39. A bezel ring 40 is held 30 in the flange 37 either by friction or by bending the flange 37 slightly inwardly. The peripheral flange 36 is bent slightly upwardly at one part to form a thumb hold 140 (Fig. 3).

35 The mirror section 3 is hingedly connected to the bezel ring 8 and is provided with a hinged knuckle 41 which may be secured to the section by solder or may be struck out from the metal thereof. The flat portion 11 of the bezel ring is provided with holes 42 and a pintle wire 43 passes through the hinge knuckle, is bent at right angles and passes through the two holes 42 and is again bent at right angles, as illustrated in Fig. 6.

40 To hold the covers in a closed position to prevent accidental opening thereof, a catch 46 is provided having an integral hinge knuckle 47. Through this knuckle is a pintle wire 48 which also passes through holes 49 provided in the flat side wall 4. The pintle wire 48 is then bent inwardly on the side wall, as illustrated in Fig. 8. The catch 46 has a hole 50 which is adapted to accommodate a pin 51 on the side 18 of the top cover to hold the case shut.

45 It will be noted that the bezel ring 8 in the base cover provides a recess or seat for the mirror 3 and that this bezel ring projects above the side walls 4 of the cover and thus aids in centering the top cover on the base cover in closing. The hinge knuckle 41 connected to the mirror section is small and the hinge construction is such that it takes up a minimum amount of space. Furthermore, the hinge of the catch 46 is neat and small. 50 The catch is of such nature as to be easily

operated, will not get out of order and does not detract from the general pleasing appearance of the vanity case. In addition, the shape of the bottom walls of the covers, having a flat annular edge portion and a central circular dome portion, springing from a point within the polygonal edge, not only adds to the appearance of the case but lends itself to a very simple and rugged construction for holding the compacts in place by the 75 bezel rings.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. A vanity case comprising a cover having a polygonal, cylindrical side wall, a bottom having an outer annular flat portion connecting with said cylindrical portion and a circular convex domed portion rising above said flat portion, a bezel ring having a polygonal edge fitting in said cover and a circular depending inner flange, a circular convex compact backing fitting said domed portion and held by said bezel ring, and a second cover cooperating with said first cover.

2. A vanity case comprising a pair of covers each having a polygonal cylindrical side wall, each cover having a bottom having an outer annular flat portion connecting with said cylindrical portion and a circular convex domed portion rising above said flat portion, a bezel ring having a polygonal edge fitting in one of said covers and a circular depending inner flange, a toilet article held by said bezel ring, said bezel ring extending above the edge of the wall of its cover.

3. In a vanity case, a cover comprising a polygonal cylindrical side wall, a bottom having an outer annular flat portion connecting with said cylindrical portion and a convex domed portion rising above said flat portion, and a second cover cooperating with said first cover to close said case, a toilet article in said first cover fitting said domed portion and means holding said toilet article in said first cover.

4. A vanity case comprising first and second covers having polygonal side walls, hinge means connecting corresponding first side walls of said covers, a flat catch having a hinge knuckle, a second side wall of the first cover having peripherally spaced holes, a pintle wire in said knuckle and in said holes, means for connecting the corresponding second side wall on the second cover and said catch including a pin and hole for said pin.

5. A vanity case comprising first and second covers having polygonal side walls, hinge

means connecting corresponding first side walls of said covers, a flat catch having a hinge knuckle, a second side wall of the first cover having peripherally spaced holes, a pintle wire in said knuckle and in said holes, a projection secured to the corresponding second side wall on the second cover, said catch having a hole for said projection.

6. A vanity case comprising a cover, a separated bezel ring retained therein, said ring having a flat annular portion at the edge of the cover, a mirror section having a hinge knuckle and seating on said ring, said knuckle resting on said flat portion, said flat portion having annularly spaced openings, and a pintle wire passing through said knuckle and said openings.

7. A vanity case comprising a cover, a separate bezel ring retained therein, said ring having a flat annular portion at the edge of the cover, a mirror section comprising a body portion and an annular flange and having a hinge knuckle, a mirror disposed in said body portion, said body portion seating within said ring, said flange and knuckle resting on said flat portion, said flat portion having annularly spaced openings, and a pintle wire passing through said knuckle and said openings, said annular flange being deformed at one part for a finger piece.

8. A vanity case comprising a cover having a polygonal, cylindrical side wall, a bottom having an outer annular flat substantially plane portion connecting with said cylindrical portion and a central domed portion rising above said flat portion, a bezel ring having a polygonal outer edge fitting said side wall, a compact backing fitting said domed portion and held by said bezel ring, a cosmetic compact molded in said backing and a second cover cooperating with said first cover.

9. A vanity case comprising a cover having a polygonal, cylindrical side wall, a central outwardly domed bottom wall connecting with said side wall, a separate bezel ring having a polygonal outer edge fitting said side wall, a compact backing fitting said domed portion and held by said bezel ring, a cosmetic compact molded in said backing and a second cover cooperating with said first cover.

10. A vanity case comprising a first section having a portion provided with spaced holes passing therethrough, a cooperating section seating on said first section and having a hinge knuckle extending between said holes, a pintle wire having a first part in said knuckle and additional parts disposed at an angle to said first part, said additional parts passing through said holes and bent under said portion whereby to hinge said sections together, and cosmetics carried in said case.

In testimony whereof I have hereunto set my hand.

CHARLES N. CORYELL.
